CLAIM

What is claimed is the ornamental design for a shade structure, as shown and described.

DESCRIPTION

FIG. 1 is a front perspective view of an embodiment of the new shade structure of Applicant's invention.

FIG. 2 is a front view thereof.

FIG. 3 is a rear view thereof.

FIG. 4 is a side view thereof.

FIG. 5 is a side view thereof.

FIG. 6 is a top view thereof.

FIG. 7 is a bottom view thereof.

FIG. 8 is a top perspective view of an additional embodiment of the shade structure.

FIG. 9 is a front view of the additional embodiment of the shade structure.

FIG. 10 is a rear view of the additional embodiment of the shade structure.

FIG. 11 is a side view of the additional embodiment of the shade structure.

FIG. 12 is a side view of the additional embodiment of the shade structure.

FIG. 13 is a top view of the additional embodiment of the shade structure; and,

FIG. 14 is a bottom view of the additional embodiment of the shade structure.

1 Claim, 10 Drawing Sheets
